(57) **CLAIM**

The ornamental design for an ice fishing pan, as shown and described.

DESCRIPTION

FIG. 1 is a perspective view of an ice fishing pan in an environment of use showing the new design;

FIG. 2 is a top perspective view of an ice fishing pan showing the new design;

FIG. 3 is a bottom perspective view thereof;

FIG. 4 is a top plan view thereof;

FIG. 5 is a side elevational view thereof; and,

FIG. 6 is a bottom plan view thereof.

In the drawings, the broken lines depict environmental subject matter only and form no part of the claimed design.
